UNITED STATES PATENT OFFICE

STANLEY K. SMITH, OF WESTFIELD, MASSACHUSETTS, ASSIGNOR TO THE H. B. SMITH COMPANY, OF WESTFIELD, MASSACHUSETTS A CORPORATION OF MASSACHUSETTS

CLOSURE

Original application filed May 24, 1929, Serial No. 365,629. Divided and this application filed January 21, 1930. Serial No. 422,382.

This invention relates to an improved construction of closure members and related attachments, and particularly relates to cast closures suitable for heaters or boilers, which are provided with outwardly extending elements to facilitate their movement. This application is a division of my copending application Serial No. 365,629, filed May 24, 1929.

- 10 In accordance with the present invention, a closure or door may be formed of molded or cast material such, for example, as cast iron, and may be provided with a sheet metal extension which is adapted to permit the convenient movement of the closure. Thus the sheet metal element may conveniently engage a suitable controlling element, such as a pull-chain or rod, that is connected to automatic control mechanism. Preferably the sheet 20 metal element may be formed of comparatively ductile material so that it may be twisted after the door or closure is cast to permit the ready connection of the control chain thereto and movement of the door by 25 the chain. A construction of this character permits the provision of inexpensive extensions for cast elements, which are firmly secured thereto and which are not liable to be broken or fractured as would be the case 30 were cast projections to be provided, while distortion of the ductile extensions due to accidental blows or the like may be readily remedied.

Referring to the accompanying drawing, 35 Fig. 1 is a front elevational view of a portion of a cast door and sheet metal extension having its end embedded in the same;

Fig. 2 is a similar view showing the manner in which the sheet metal extension may be 40 twisted to meet the requirements of use;

Fig. 3 is an elevational detail of a portion of a boiler with associated thermostatic control mechanism and a chain connection between the same and the swinging closure or 45 draft door;

Fig. 4 is a side elevational view of the door showing the connection of the same to the control chain; and

Fig. 5 is a section on line 5—5 of Fig. 2. 50 In accordance with the present invention,

the door 60 may be formed of cast metal, having a dished formation which provides a continuous marginal flange 48. This door may be of any suitable shape and may have one or more integral extensions 58, each of 55 which may be provided with an opening 57 which is adapted to engage a hinge pintle and therefore is effective in defining a hinge axis. The door may be provided with an integral internal lug 59 which is joined to its marginal 60 flange portions at a corner remote from the hinge extension 58. When the door or closure 60 is cast, the inner end of a sheet metal element S may be disposed or embedded within the integral lug 59. The outer end of this 65 element may be provided with an opening 69 and its inner end may have an opening 51 which becomes filled with the cast metal and permits the same firmly to interlock with the embedded end of the sheet metal element. 70

As shown in Fig. 1 the strip S may initially occupy a position wherein it is disposed entirely in a plane which is substantially parallel to the end of the door and at right angles to the axis defined by its hinge extension 58. Since the strip S is formed of comparatively ductile material, it may be twisted to the desired shape properly to receive a control chain. For this purpose the portion of the strip adjoining the surface of the door 60 80 may have a bend 63 (Fig. 5) so that the end of the strip is disposed outwardly of the end of the door, as shown in Fig. 2, and this end portion of the strip may be then twisted as designated by numeral 54 into a plane which 85 is substantially horizontal, i. e., parallel to the hinge axis of the door. It is thus evident that the ductility of the strip S permits the twisting of the same while cold properly to position the opening 69 at the desired point 90 in relation to the door.

Fig. 3 illustrates a typical manner of installing a closure of this character in a boiler of the general type disclosed in my prior copending application referred to above, the door 60 being disposed below the firebox 61 to afford a controllable closure for air passing into the firebox. The exact position of this closure may be determined by the control element 49 which is connected to suitable ther- 100

mostatic control mechanism 64 so that the position of the door is varied in accordance with the movement imparted thereto by element 49 due to the action of the control mechanism.

Preferably element 49 extends through opening 69 and carries an abutment member 70 which may engage the lower face of element S when the door is partially opened. 10 Since the door is hinged at its upper end, as shown, the weight of its depending lower portion ordinarily will tend to maintain the outer end of the element S in engagement with the member 70.

15 As shown in Fig. 5 the cast metal ordinarily will fill the opening 51 and the inner end of the strip S accordingly is firmly embedded in and interlocked with the cast material of the door, while its outer end may be 20 readily positioned as required. Obviously this arrangement permits the sheet metal section to be disposed to receive the imposed strains advantageously and to locate its chain-engaging portion at one side of the end 25 of door 60, while accidental twisting or bending of the element S due to shocks or accidental blows will not be likely to cause its breakage or loosening; and if it is distorted from its proper shape, it may be readily bent 30 and returned to this shape. While the door 60 is here shown as an ashpit door, it is intended as representative of any draft control door or damper.

I claim:

25 1. A door having a body portion with a dished formation providing an integral marginal flange, an extension of said flange upon one edge of the closure defining a hinge axis about which the closure may swing, an internal lug projecting from the body portion of the door and its flange, said lug being integral with the marginal flange at the edge of the door opposite said extension, and a control element of ductile strap material having its inner end embedded in the metal of the lug and its outer end projecting from the door, the inner end of the control element being disposed in a plane substantially at right angles to the direction of extent of said hinge axis, the element having an intermediate twisted portion disposed adjoining the surface of the door, and having its outer end disposed in a plane which is substantially parallel to said hinge axis, the outer end of the element being shaped for connection with a control member to swing the door about its hinge axis whereby the embedded portion of the control element is disposed with its maximum dimension positioned in the direction of a normal strain imposed thereon by the control member to swing the door about its hinge axis.

30 2. A door having a substantially rectangular cast body portion with a dish formation 35 providing an integral marginal flange, exten-

sions of said flange upon one side of the door defining a hinge axis about which the door may swing, an integral lug in the corner of the closure, said lug being integral with portions of the flange extending respectively at right angles to the flange adjoining the hinge axis and opposite said flange, and a metal control element of ductile strap metal having its inner end embedded in the metal of the lug and having an opening through which the metal of the lug extends, said element having its inner end disposed in a plane substantially at right angles to the hinge axis, having a twisted intermediate portion and having its outer portion disposed in a plane substantially parallel to the hinge axis, said outer portion having an opening for connection to a flexible control member adapted to be pulled to swing the door about its hinge axis.

Signed by me at Westfield, Massachusetts, this 31st day of December, 1929.
